UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTOR DEVICE.

Application filed December 12, 1919. Serial No. 344,301.

To all whom it may concern:

Be it known that I, REUBEN B. BENJAMIN, a citizen of the United States, residing at Chicago, in the county of Cook and State 5 of Illinois, have invented new and useful Improvements in Electrical Connector Devices, of which the following is a full, clear, concise, and exact description, reference being had to the accompanying drawing, 10 forming a part of this specification.

This invention relates to electrical connector devices.

In some lighting systems, and especially in farm lighting systems, low voltage is 15 generally used. To obtain the same lighting power with low voltage, as is obtained with the higher voltage circuits, it is necessary that the translating devices used (such as lamps, heaters, and so forth) be 20 of low resistance so that a high amperage is necessary. Therefore, where plug-in devices are to be inserted into receptacles, this high amperage at the point of connection would burn out the contacts unless a quick 25 and positive connection is made between the plug and receptacle.

It is therefore one object of my invention to provide improved means whereby a quick and positive connection is provided 30 between these parts, thereby preventing arcing and burning out of the contacts.

Another object of this invention is to provide an improved connector device which is so constructed as to form a compact and 35 neat arrangement of parts and which will be simple, cheap to manufacture, durable and efficient in use.

Further objects will appear from the detailed description and appended claims.

40 In the drawings—

Fig. 1 is a longitudinal sectional view of a connector device showing the parts in their relative position before engagement;

Fig. 2 is a sectional view on the line 2—2 45 of Fig. 1;

Fig. 3 is a longitudinal sectional view of the connector device with the parts in engagement;

Fig. 4 is a view taken on the line 4—4 50 of Fig. 1 looking in the direction of the arrows; and

Fig. 5 is a view taken on the line 5—5 of Fig. 2.

In order to give a general idea of the 55 invention, it is here stated that the construc-

tion shown comprises a receptacle 10, having a pair of wiring terminals 11 and 12 for the feed wires and two pair of spring contact devices 13—14 and 15—16 respectively, electrically connected with the wiring terminals respectively, for engagement with the contact blades 17 and 18 mounted on the cap 20. An insulated pin 19 is embedded in the cap 20 which insulated pin extends between an upwardly extending 60 spring finger 21 and the contact finger 15. As shown in Fig. 1, the circuit will not be completed upon first engagement of the blade 17 with the contact fingers 13 and 14 due to the fact that the spring contact 70 fingers 15 and 16 are separated to a greater extent than the width of the blade 18 whereby they do not engage each other.

Upon insertion of the plug-in device, however, the insulated pin 19 will separate 75 the finger 21 and the contact finger 15 which it engages and will correspondingly decrease the space between the contact fingers 15 and 16 so that the fingers will engage the blade 18 which has been inserted 80 therebetween. The contact fingers 13 and 14 are always in position to engage the blades 17 so that after the insulated pin is inserted as mentioned, and the contact fingers 15 and 16 engage the blades 18, the 85 circuit will be completed. The construction of the fingers engaging the insulating pin is such that they form a substantial yielding resistance to the insertion of the plug-in device whereby the operator, upon 90 meeting this resistance, will give an energetic push on the cap to further insert the blades 17 and 18 and cause a quick electrical connection between the contacting members, thereby completing the circuit. 95.

To give a more detailed description of my construction, the receptacle portion 10 comprises a base portion 26 to which the wiring terminals 11 and 12 and spring contacts 13, 14, 15 and 16 are secured and a 100 cover portion 22 having a recess 23 into which the spring contact members extend, and having restricted openings 24 leading to the recess, said openings providing a passage for the contact blades of the plug-in device. The binding plates 11 and 12 are secured in recesses 26 and 27 in the insulating base 26 by screws 28 and threaded into said plates are the binding screws 29 by which suitable conductors may 105 110

be securely held. The binding plate 11 has an upturned portion 30 which has riveted thereto the two spring contact fingers 13 and 14 which are positioned to engage the 5 contact blade 17. The contact fingers 15 and 16 and the central finger 21 are bent at right angles at their lower ends and are held between the binding plate 12 (which may be a flat metal stamping) and the insulating base 26 by the screws 28 which secure the binding plate 12 on the insulating base. The central finger 21 and contact fingers 15 and 16 are slotted substantially intermediate their ends whereby a connecting 10 member 31, which may be a suitable metal stamping, may be inserted in said slots passing through the slot in the contact finger 15 and engaging the central finger 21 and the contact finger 16 to connect these 15 two last mentioned members to cause them to move together, the contact finger 15, however, being independently movable with respect to the fingers 21 and 16 and the connecting member 31. The central finger 20 terminates in a curved portion which engages a corresponding grooved portion near the end of the insulated pin 19 whereas the contact finger 15 is formed into a hook at its upper end. 25

30 The cover portion 22 is secured to the base member by means of long screws 32 (Fig. 2) which are screwed into suitable bushings embedded in the insulating base of the receptacle. A recess 23 is formed in the cover 35 into which the contact fingers and the central finger extend. Suitably located in said cover portion to afford an entrance for the contact blades and an insulated pin for engagement with the spring fingers are the restricted openings 24.

40 The cap 20 comprises an insulating base 32^a which has the contact blades 17 and 18 mounted thereon. The blades are secured to said base by means of screws 33 threaded 45 into binding plates 34 which are integrally formed with said blades and bent at right angles thereto whereby they lie in a horizontal plane (Fig. 4). The binding screws 35 are threaded into said integrally formed 50 plates 34 and securely hold suitable conductors. The insulated pin 19, as before mentioned, is embedded in the insulating base 32. The cord grip bushing 25 is threaded into a correspondingly threaded portion in 55 the insulating base and has an aperture therein for the passage of suitable conductors.

60 The use and operation of the construction described herein is as follows: When the plug-in device is to be inserted into the receptacle portion, the insulated pin is inserted in the central slot of the three slots 24 until it engages the central finger 21 and the contact finger 15. The contact blade 17 will 65 also engage the contact fingers 13 and 14 at

this time but no electrical circuit will be completed due to the fact that the contact blade 18 is not in engagement with the contact fingers 15 and 16 which are separated as shown in Fig. 1. At this point of initial 70 engagement, a substantial resistance is encountered before the circuit is completed, the encountering of this resistance by the operator causing him to give a quick and energetic push of the plug-in device for further insertion into the receptacle portion. The result of this action will be to insert the contact blade 17 between the contact fingers 13 and 14 and the insulated pin 19 between the central finger 21 and the hook portion 80 of the contact finger 15 which action will draw the contact finger 16 inwardly due to its being connected with the central finger 21 by the connecting member 31 and the finger 15 will be moved outwardly whereby 85 the contact blade 18 will be received between the fingers 15 and 16 to electrically connect the blades and contact fingers and complete the circuit.

Having thus described my invention, what 90 I claim as new and desire to secure by Letters Patent is:

1. A connector device comprising a plug-in portion and a receptacle portion, said plug-in portion comprising an insulating 95 base, a contact blade and a pin, said pin and blade being supported by said insulating base, and said receptacle comprising two contact fingers between which said blade extends, and a third finger between which and one of said contact fingers said pin extends and a connecting member connecting one of said contact fingers to said third finger to prevent relative movement between the connector fingers, whereby when said plug-in 100 portion is inserted, the pin will separate the members between which it is inserted to force the fingers between which the blade is inserted against the blade.

2. A connector device comprising a plug-in portion and a receptacle portion, said plug-in portion comprising an insulating base, contact blades thereon and a pin, said pin and blades being supported by said insulating base, and said receptacle comprising a plurality of contact fingers between which said blades extend, and a central finger between which and one of said contact fingers said pin extends and a connecting member connecting one of said contact fingers and said central finger to prevent relative movement between the connector fingers whereby when said plug-in device is first inserted, no electrical circuit is completed, but upon further insertion of the 115 plug-in device, the pin will separate the members between which it is inserted to force the fingers between which one of the blades is inserted against said blade to complete the circuit and form an electrical con- 120 130

nection between the plug-in device and the receptacle.

3. An electrical connector device comprising a plug-in portion and a receptacle portion, said plug-in portion comprising an insulating base, a pair of contact blades and a pin, said blades and pin being insulated from each other by said insulating base, said receptacle comprising an insulating base, a 10 pair of contact devices for cooperation with said contact blades respectively and a resistance device for offering mechanical resistance to the entry of said pin, an insulat-

ing cover for said contact devices and resistance member, said insulating cover being 15 recessed to receive said contact devices and resistance member, said insulating cover being provided with a pair of openings for the entrance of said blades for engagement with said contact devices, and being provided 20 with another opening for the entrance of said pin for engagement with said resistance member.

In witness whereof, I have hereunto subscribed my name.

REUBEN B. BENJAMIN.
